UNITED STATES PATENT OFFICE

2,100,540

PRESSURE FLUID MOTOR

Elmer G. Gartin, Claremont, N. H., assignor to
Sullivan Machinery Company, a corporation
of Massachusetts

Application November 1, 1934, Serial No. 751,010

12 Claims. (Cl. 121—12)

This invention relates to pressure fluid motors, and more particularly to improved blow-varying means for a pressure fluid actuated motor of the reciprocating piston type.

An object of this invention is to provide an improved pressure fluid motor. Another object is to provide improved blow-varying means for a pressure fluid motor of the reciprocating piston type. Yet another object is to provide an improved pressure fluid motor of the reciprocating piston hammer type having embodied therein improved means for varying the force of the blow of the hammer piston so that a light, medium or heavy blow may be struck by the piston, as desired. Still another object is to provide an improved pressure fluid motor of the impact type especially designed to use in hammer rock drills and having embodied therein improved blow-varying means for varying the blow of the hammer piston to suit different drilling conditions. These and other objects and advantages of the invention will, however, hereinafter more fully appear.

In the accompanying drawings there are shown for purposes of illustration two forms which the invention may assume in practice.

In these drawings,—

Fig. 1 is a longitudinal section through a hammer rock drill having embodied therein one illustrative form of the improved pressure fluid motor.

Fig. 2 is a view similar to Fig. 1 showing the moving motor parts in a different position.

Fig. 3 is a cross sectional view taken on line 3—3 of Fig. 2.

Fig. 4 is a cross sectional view taken on line 4—4 of Fig. 2.

Fig. 5 is a detail sectional view taken on line 5—5 of Fig. 4.

Fig. 6 is a detail sectional view taken on line 6—6 of Fig. 3.

Figs. 7 and 8 are views similar to Fig. 3 on a somewhat enlarged scale showing the valve chest member, by which the piston blow is varied, in different positions.

Figs. 9 and 10 are detail sectional views taken on lines 9—9 and 10—10, respectively, of Fig. 7.

Figs. 11 and 12 are detail sectional views taken on lines 11—11 and 12—12, respectively, of Fig. 8.

Fig. 13 is a front end elevational view of the valve box.

Fig. 14 is a rear end elevational view of the valve box cover.

Fig. 15 is an enlarged view similar to Fig. 1 showing a modified form of the invention, the view taken on line 15—15 of Fig. 16.

Fig. 16 is a cross sectional view taken on line 16—16 of Fig. 15.

Figs. 17 and 18 are views similar to Fig. 16 showing the blow-varying control parts in different positions.

Fig. 19 is a detail sectional view taken on line 19—19 of Fig. 15.

In the illustrative embodiment of the invention shown in Figs. 1 to 14, inclusive, the improved blow-varying means is embodied in a rock drill of the pressure fluid actuated hammer type comprising a cylinder 1 having a bore 2 containing a reciprocating hammer piston 3. The hammer piston has a head 4 fitting the cylinder bore 2 and a forwardly projecting piston rod 5 in the form of a striking bar for delivering impact blows to the shank 6 of a usual rock drill steel. The piston rod 5 is guided in a bore 7 formed in a front cylinder head 8, and the drill steel shank is supported in a chuck member 9 carried by a chuck sleeve 10 rotatably mounted in a front chuck housing 11 in a well known manner.

In the rear end of the cylinder is an enlarged bore 12 in alignment with the cylinder bore and closed at its rear end by a head block 13, and arranged in this enlarged bore is valve mechanism generally designated 14 and rotation mechanism designated in general by 15.

The rotation mechanism may be of a well known type comprising a ratchet ring 16 disposed in the extreme rear end of the bore 12 and serving, in this instance, as a seat for the rear head block 13. On the inner periphery of this ring are the usual ratchet teeth 17 to act as abutments for usual pawls 18 carried by a pawl carrier 19 integral with a rifle bar 20. This rifle bar extends, in the present instance, through the valve mechanism 14 to engage interlockingly a rifle nut 21 secured within the motor piston 3. The piston rod 5 has straight flutes 22 interlocked with straight ribs 23 on a chuck nut 24 threadedly secured within the chuck sleeve 10. As the motor piston moves rearwardly the pawls 18 engaging the teeth of the ratchet ring hold the rifle bar 20 against rotative movement, and as a result, rotative movement is imparted to the motor piston, and this rotative movement is transmitted through the straight flutes 22 on the piston rod and the straight ribs on the chuck nut 24 to the drill steel 6 so that, as the latter is percussively actuated, it is at the same time rotated.

The valve mechanism 14 with which the improved blow-varying means is associated, comprises a valve box 25 abuttingly engaging a valve box cover 26, the valve box and cover being ar-

ranged in the bore 12 between the inner wall of the bore and the ratchet ring 16. In the present construction, formed in the valve box 25 and surrounding the rifle bar 20 is an annular valve chamber 27 having reciprocably mounted therein an annular flat disc or plate valve 28. This valve is provided with a central bore 29 and is slidably mounted upon and guided by the cylindrical portion of the rifle bar 20 in the manner shown. Formed on the valve box and cover, respectively, at the opposite sides of the valve chamber are annular grooves 30 and 31, while arranged concentrically within these grooves are annular grooves 32 and 33. Also formed in the cover 26 in concentric relation with the grooves 31, 33 is an outer arcuate groove 34 clearly shown in Fig. 14. In the present construction the valve chamber is of slightly larger diameter than the valve element 28 to provide a restricted annular passage past the peripheral edge of the valve through the valve chamber. Arranged in the head block 13 is a throttle valve 35 having a central supply chamber 36 communicating with any suitable pressure fluid source, and this central chamber is connected by a radial passage 37 to a passage 38 in turn communicating with an annular supply chamber 39. The chamber 39 communicates through the space formed between the ratchet teeth of the ratchet ring 16 with an annular recess 40 formed in the rear face of the valve box 25, and this recess is connected by a series of longitudinal passages 41 with the annular groove 34. The central annular groove 31 formed in the rear face of the valve box cover is communicable with the rear end of the cylinder bore through a series of longitudinal passages 42. The outer groove 30 formed in the valve box is communicable with the front end of the cylinder bore through a pair of radial passages 43 formed in the valve box and ports 44, longitudinal passages 45 and ports 46. Formed in the wall of the cylinder intermediate the ends thereof is an annular piston chamber exhaust groove 47 communicable through a free exhaust port 48 with the atmosphere. The groove 33 in the rear face of the valve box cover is constantly supplied with pressure fluid through a passage 49 communicating with the supply groove 34, while the groove 32 is constantly supplied with pressure fluid through passages 50 communicating through the ratchet ring with the supply chamber 39.

When the parts are in the position shown in Fig. 1, pressure fluid may flow from the throttle valve through passage 38, supply recess 39 and thence through the spaces between the ratchet teeth, recess 40, the series of longitudinal passages 41, supply groove 34, through the valve chamber past the forward face of the valve 28 and through groove 31 and passages 42 to the rear end of the cylinder bore, the pressure fluid acting on the rear face of the motor piston to drive the latter forwardly to effect its working stroke, i. e. to strike an impact blow to the shank 6 of the drill steel. At this time the forward end 60 of the cylinder bore is open to exhaust through groove 47 and exhaust port 48, and as the piston travels forwardly the groove 47 is cut off by the piston head, and upon continued forward movement a substantial compression pressure is built up by the piston within the forward end of the cylinder bore. As the rear edge of the piston head overruns the exhaust groove 47, the rear end of the cylinder bore is connected to exhaust through exhaust port 48, and as a result the pressure within 75 the rear end of the cylinder bore and in the

groove 31 is substantially reduced. The compression pressure built up within the forward end of the cylinder bore, passages 45, 45 and groove 30, aided by the pressure fluid in the concentric groove 32, overcomes the opposing reduced pressure in the groove 31 and the pressure fluid in groove 33, thereby throwing the valve from the position shown in Fig. 1 to the position shown in Fig. 2. When the parts are in the position shown in Fig. 2, the valve is held against the rear face 1 of the valve box cover, cutting off communication between the rear end of the cylinder bore and the annular supply groove 34, and pressure fluid then flows from the groove 34 through the valve chamber past the outer periphery of the valve, through groove 30, passages 43, ports 44, passages 45 and ports 46 to the forward end of the cylinder bore, the pressure fluid acting on the forward pressure area of the motor piston to drive the latter rearwardly to effect its retraction stroke. At this time the pressure at the rearward end of the cylinder bore is connected to exhaust through groove 47 and exhaust port 48, and as the piston moves rearwardly the exhaust groove 47 is overrun by the piston head, and upon continued rearward movement of the piston a substantial compression pressure is built up within the rear end of the cylinder bore. As the piston moves rearwardly, the forward edge of the piston head overruns the exhaust groove 47, connecting the forward end of the cylinder bore to exhaust, and as a result, the pressure within the forward end of the cylinder bore and in passages 45 and groove 33 at the rear side of the valve is substantially reduced. The compression pressure 30 in the rear end of the cylinder bore and groove 31 at the forward side of the valve aided by the pressure fluid in the groove 33 overcomes the reduced pressure in the groove 30 and the pressure fluid in groove 32, and as a result, the valve is 40 thrown from the position shown in Fig. 2 to the position shown in Fig. 1, these operations being rapidly repeated during normal operation of the motor.

Now referring to the improved blow-varying 45 means, it will be noted that the valve box 25 and its cooperating cover 26 are maintained against rotative movement within the bore 12 by a dowel pin 55, and in this instance the valve box cover 26 is provided with a series of parallel grooves, 50 herein preferably three, numbered 56, 57 and 58 so that this cover may be rotated with respect to the cylinder into three different predetermined positions within the bore 12. The valve box is provided with a single longitudinal groove 59 so 55 that the valve box is always held against rotative movement by the dowel pin 55, the valve box cover being adjustable into its different positions with respect to the relatively stationary valve box. In this instance, the inner wall of the bore 12 is ar- 60 cuately grooved at 60, and the fluid supply groove 34 is at one end communicable with the groove 60 through a port 61, as clearly shown in Figs. 7 and 8, while the adjustable valve box cover 26 is provided with a pair of auxiliary passages 62 and 63 65 for connecting the groove 33 with the groove 60, as clearly shown in Figs. 9 and 10. The relatively stationary valve box 25 is also provided with a pair of auxiliary passages 64 and 65 for connecting the groove 32 with the groove 34. The pas- 70 sages 62 and 63 extend radially through the exterior periphery of the valve box cover, while the passages 64 and 65 extend longitudinally through the forward face of the valve box, and in the positions of the valve box cover as shown in Figs. 6 75

and 9, the passages 62 and 63 are blanked off by the wall of the bore 12 and the passages 64 and 65 blanked off by the rear face of the valve box cover in the manner shown in Fig. 5.

5 When the valve box cover is in the position shown in Fig. 3, the motor, as described above in regard to Figs. 1 and 2, operates in a normal manner to deliver a full impact blow with full piston stroke, and when the parts are so adjusted, the 10 drilling motor is adapted to drill in relatively hard rock. When it is desired to drill under relatively soft drilling conditions, it is desirable to lessen the intensity of the blow of the motor piston to deliver a relatively light blow to the drill 15 steel shank. During this soft drilling condition the valve assembly is removed from the cylinder and the valve box cover is adjusted with respect to the valve box to the position shown in Fig. 8 by removing the dowel 55 and turning the cover 20 so that the dowel engages the groove 58. When the valve box cover is in the position shown in Fig. 8, the passages 62 and 63 are in communication with the groove 60 so that through these passages 62 and 63 an auxiliary supply of pressure fluid, 25 supplementing the pressure fluid in the passages 49, 49, is conducted to the groove 33, while at the same time an auxiliary supply of pressure fluid supplementing the flow through the passages 50, 20 50, is conducted to the groove 32 through the passages 64 and 65 at that time communicating with the groove 34. Accordingly, since there is an additional flow of pressure fluid to the grooves 32 and 33, the throwing action of the distributing valve 28 is materially quickened while at the same 30 35 time there is an increased volume of pressure fluid supplied through the valve chamber to the grooves 30 and 31 connected to the opposite ends of the cylinder bore.

While the rate of travel of the valve while it is 40 moving may not be increased, and while the positions occupied by the piston at the instant of valve throwing may not be altered, the admission of greater quantities of motive fluid to the rear end of the cylinder after the valve is thrown and 45 before the piston reaches its extreme rear position, will diminish the distance the piston travels rearwardly. In other words, the rearward stroke of the piston will be shortened, and accordingly the piston will not attain, on its striking stroke, 50 the same momentum which attends its full-length stroke when the passage 49 is in communication with the groove 33. Moreover, because of the increased quantity of fluid which is admitted to the forward end of the cylinder during the forward stroke of the piston, after the rear end of 55 the piston has uncovered the exhaust port and allowed the valve to be thrown to position for the rearward stroke, there will be a somewhat increased cushioning effect because the piston will 60 make the last portions of its working stroke against a somewhat higher pressure in the forward end of the cylinder. It will thus be appreciated (1) that the initial momentum of the piston will be reduced, surprising though this may seem, and (2) that from that momentum there will be a greater subtraction due to the increased quantity of air entering the forward end of the cylinder before the piston strikes the steel. Therefore, 65 while the motor is not short-stroked very materially in the sense of its forward travel (the difference will be merely in the amount of penetration of the drill steel, as a practical matter), there will be a definite lightening of the blow and 70 a variation of the rate of drilling possible when 75

it is desired for any reason not to have too great a penetration.

When it is desired to operate the motor piston in a medium position, that is during drilling conditions substantially midway between hard drilling and soft drilling, the valve assembly is removed from the cylinder and the valve box cover is adjusted relative to the valve box into its intermediate position shown in Fig. 7 with the dowel 55 engaging the middle groove 57 on the cover, so that the supply of pressure fluid to the grooves 32 and 33 is supplemented by but a single passage 63 and a single passage 65, the other passages 62 and 64 being blanked off by the wall of the bore 32 and the inner face of the valve box cover, respectively. It is evident that when one of each of the passages 62, 63 and 64, 65 is blanked off, the auxiliary supply of pressure fluid to the grooves 32 and 33 is cut substantially in half so that the throwing action of the valve and the intensity of the blow of the piston, due to the increased volume of air flowing to the cylinder is substantially midway between the full blow position shown in Fig. 3 and the light-blow position shown in Fig. 8.

In the modified form of the invention shown in Figs. 15 to 19, inclusive, the pressure fluid motor is similar to that shown in Fig. 1, but the means for supplementing the supply of pressure fluid to the grooves 32 and 33 is somewhat changed. In this instance, there is arranged a rotatable control member 68 mounted in a bore 69 in the cylinder and having an operating handle 70. This member 68 is provided with a central passage 71 communicable through the passage 72 with the port 37 of the throttle valve 35. The inner wall of the bore 69 is grooved at 73 and the member 68 is provided with a pair of radial passages 74 and 75 for connecting the passage 71 with the groove 73. Communicating with the groove 73 is a longitudinal passage 76 connected through a port 77 with a groove 78 and passages 79 communicating with the groove 32, and through a port 80 communicating with a groove 81 and passages 82 in turn communicating with the groove 33. In this instance the valve box 25 and valve box cover 26 are held against rotative movement in the bore 12 by a dowel pin 55 engaging aligned grooves in the valve box cover. When the control member 68 is in the position shown in Fig. 16, the pressure fluid motor operates with full piston stroke to deliver a full impact blow to the drill steel shank. When it is desired to lighten the intensity of the blow of the motor piston during soft drilling conditions, the operator grasps the handle 70 to rotate the control member 68 from the position shown in Fig. 16 to the position shown in Fig. 18. At this time the flow of pressure fluid to the groove 32 through the passages 50, 50 is supplemented by the pressure fluid flowing through passage 71, passages 74, 75, groove 73, passage 76, groove 78 and auxiliary passages 79, 79, while the flow of pressure fluid to the groove 33 through the passages 49, 49 is supplemented by the flow of pressure fluid from passage 76 through passage 80, groove 81 and passages 82, 82. As a result, there is increased pressure in the grooves 32, 33 which quickens the throwing action of the valve, while at the same time an increased volume of pressure fluid flows through grooves 30 and 31 to the opposite ends of the cylinder bore, thereby causing a back pressure to build up in the opposite ends of the cylinder bore which causes lightening of the motor piston in the manner clearly described 75

above in connection with the first form of the invention. When it is desired to operate the pressure fluid motor to suit a medium drilling condition, the control member 68 is rotated into the position shown in Fig. 17 with only one passage 79, 82 supplying pressure fluid to the grooves 32 and 33. Otherwise this form of the invention is the same as that above described.

The results of changing rate of fluid supply to the grooves 32 and 33 will be more readily appreciated when it is noted there is a pressure drop in each of these grooves once in each cycle, and that the cumulative pressures in these grooves and compression pressures time valve throw.

As a result of this invention, it will be noted that an improved pressure fluid motor is provided having embodied therein improved and simplified means for varying the blow of the motor piston, it being possible to vary the piston blow to suit different drilling conditions. It will further be noted that by utilizing the valve box cover as a control element for the blow varying means, it is possible to effect a variation in the piston blow by means of a very simple change in adjustment of parts, it being necessary only to rotate the valve box cover slightly with respect to the valve box to effect such blow-varying function. Other uses and advantages of the invention will be clearly apparent to those skilled in the art.

While there are in this application specifically described two forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

1. In a pressure fluid motor, a cylinder having a bore, a piston reciprocable therein, fluid distribution means for effecting reciprocation of said piston including a valve box having a valve chamber, a valve box cover, a fluid actuated fluid distributing valve reciprocable in said valve chamber, valve throwing means, and means associated with the fluid distribution means for varying the piston blow including said valve box cover, the latter being adjustable relative to the valve box to effect such piston blow variations.

2. In a pressure fluid motor, a cylinder having a bore, a piston reciprocable therein, fluid distribution means for effecting reciprocation of said piston including a valve box having a valve chamber, a valve box cover, a fluid actuated fluid distributing valve reciprocable in said valve chamber, valve throwing means, and means associated with the fluid distribution means for varying the volume of the pressure fluid flowing past said valve to the cylinder bore to vary the piston blow and including said valve box cover, the latter being adjustable relative to the valve box to effect such piston blow variation.

3. In a pressure fluid motor, a cylinder having a bore, a piston reciprocable therein, fluid distribution means for effecting reciprocation of said piston including a valve box comprising relatively adjustable valve box elements cooperating to provide a valve chamber, a fluid actuated fluid distributing valve movable in said valve chamber, valve throwing means, and means associated with the fluid distribution means for varying the volume of pressure fluid flowing past said distributing valve to the cylinder bore to vary the

piston blow and including the adjustable element of said valve box, the latter being adjustable relative to the other element of the valve box to effect such piston blow variation.

4. In a pressure fluid motor, a cylinder having a bore, a piston reciprocable therein, a valve chest having a valve chamber, throttle controlled passage means for supplying pressure fluid to said valve chamber, a fluid actuated distributing valve in said valve chamber, passage means controlled by said valve for supplying pressure fluid to the opposite ends of said cylinder, and means adjustable to effect a variation in the flow area of said first mentioned passage means for varying the volume of pressure fluid flowing therethrough and through said second mentioned passage means to the opposite ends of the cylinder while the supply pressure and throttle control remain the same to vary the blow of the piston.

5. In a pressure fluid motor, a cylinder having a bore, a piston reciprocable therein, a valve chest having a valve chamber, throttle controlled passage means for supplying pressure fluid to said valve chamber, a fluid actuated distributing valve in said valve chamber, passage means controlled by said valve for supplying pressure fluid to the opposite ends of said cylinder, and means adjustable to effect a variation in the flow area of said first mentioned passage means for varying the volume of pressure fluid flowing therethrough and through said second mentioned passage means to the opposite ends of the cylinder while the supply pressure and throttle control remain the same to vary the blow of the piston, said adjustable means including a blow-varying element adjustable into positions to effect a heavy blow, a medium blow and a light blow.

6. In a pressure fluid motor, a cylinder having a bore, a hammer piston reciprocable therein for delivering impact blows to a working implement, a valve chest having a valve chamber, throttle controlled passage means for supplying pressure fluid to said valve chamber, a fluid actuated fluid distributing valve movable in said valve chamber, passage means leading from said valve chamber to said cylinder bore and controlled by said valve for supplying pressure fluid to said cylinder bore to effect reciprocation of said piston, and means operative to provide different flows of pressure fluid past said valve during like periods of valve opening while maintaining the same opening of said second mentioned passage means leading from the valve chamber to the cylinder bore and while the supply pressure and throttle control remain the same, thereby to vary the impact blow of said piston.

7. In a pressure fluid motor, a cylinder having a bore, a hammer piston reciprocable therein for delivering impact blows to a working implement, a valve chest having a valve chamber, throttle controlled passage means for supplying pressure fluid to said valve chamber, a fluid actuated fluid distributing valve movable in said valve chamber, passage means controlled by said valve for supplying pressure fluid to the ends of said cylinder bore to effect reciprocation of said piston, and means for increasing the quantity of fluid flow to the ends of the cylinder bore in a predetermined unit of time of valve opening while the supply pressure and throttle control remain the same to vary the impact blow of said piston.

8. In a pressure fluid motor, a cylinder having a bore, a hammer piston reciprocable therein for delivering impact blows to a working implement, a valve chest having a valve chamber, throttle

controlled passage means for supplying pressure fluid to said valve chamber, a fluid actuated fluid distributing valve movable in said valve chamber, passage means controlled by said valve for supplying pressure fluid to the ends of said cylinder bore to effect reciprocation of said piston, and means for increasing the flow area opened into communication with said second mentioned fluid supply passage means leading to the opposite ends 10 of the cylinder when said valve places said valve chamber in communication with said passage means and while the supply pressure and throttle control remain the same, thereby to vary the impact blow of said piston.

15 9. In a pressure fluid motor, a cylinder having a bore, a hammer piston reciprocable therein for delivering impact blows to a working implement, a valve chest having a valve chamber, throttle controlled passage means for supplying 20 pressure fluid to said valve chamber, a fluid actuated fluid distributing valve movable in said valve chamber, passage means controlled by said valve, for supplying pressure fluid to the ends of said cylinder bore to effect reciprocation of said piston, and means for increasing the rate of fluid 25 admission to said cylinder through said second mentioned passage means for a given rate of operation of said motor in terms of blows per minute while the supply pressure and throttle control remain the same, thereby to vary the impact blow of said piston.

10 10. In a pressure fluid motor, a cylinder having a bore, a hammer piston reciprocable therein for delivering impact blows to a working implement, a valve chest having a valve chamber, throttle controlled passage means for supplying 30 pressure fluid to said valve chamber, a fluid actuated fluid distributing valve movable in said valve chamber, passage means controlled by said valve 40 for supplying pressure fluid to the opposite ends of said cylinder bore to effect reciprocation of said piston, valve throwing means, and adjustable means communicable with said second mentioned passage means for varying the volume of

pressure fluid flowing past said valve through said second mentioned passage means to the cylinder bore while the supply pressure and throttle control remain the same, to vary the impact blow of said piston.

11. In a pressure fluid motor, a cylinder having a bore, a hammer piston reciprocable in said bore for delivering impact blows to a working implement, a valve chest having a valve chamber, throttle controlled passage means for supplying 10 pressure fluid to said valve chamber, a fluid actuated fluid distributing valve movable in said valve chamber for controlling the supply of pressure fluid to the opposite ends of the cylinder bore to effect reciprocation of said piston, said valve 15 when in one position in said valve chamber admitting pressure fluid through the valve chamber past said valve to one end of said cylinder bore, and adjustable means for varying the volume of pressure fluid flowing past said valve when the 20 latter is in said position to one end of the cylinder bore while the supply pressure and throttle control remain the same, to vary the impact blow of said piston.

12. In a pressure fluid motor, a cylinder having 25 a bore, a hammer piston reciprocable in said bore for delivering impact blows to a working implement, and fluid distribution means for effecting reciprocation of said piston including means forming a valve chamber, throttle controlled passage means for supplying pressure fluid to said 30 valve chamber, a fluid distributing valve in said valve chamber, passage forming means for connecting said valve chamber with the opposite ends of the cylinder in opposite positions of said distributing valve, means for supplying motive fluid to said valve chamber, and means for effecting valve throw including means for providing variable area communication with said valve, placed in communication with said passage forming 35 means in the open positions of said valve while the supply pressure and throttle control remain 40 the same.

ELMER G. GARTIN.

CERTIFICATE OF CORRECTION.

Patent No. 2,100,540.

November 30, 1937.

ELMER G. GARTIN.

It is hereby certified that error appears in the printed specification of the above numbered patent requiring correction as follows: Page 3, second column, line 74, after "the" second occurrence, insert intensity of the blow of the; and that the said Letters Patent should be read with this correction therein that the same may conform to the record of the case in the Patent Office.

Signed and sealed this 1st day of February, A. D. 1938.

(Seal)

Henry Van Arsdale,
Acting Commissioner of Patents.
